UNITED STATES PATENT OFFICE.

ALBERT W. MENNS, OF REVERE, AND ALBERTO T. VAN HORN, OF MALDEN, MASSACHUSETTS, ASSIGNORS TO MENNS-VAN HORN MOTOR COMPANY, OF PORTLAND, MAINE, AND BOSTON, MASSACHUSETTS, A CORPORATION OF MAINE.

ENGINE-SUPPORT.

SPECIFICATION forming part of Letters Patent No. 709,445, dated September 16, 1902.

Application filed January 22, 1902. Serial No. 90,785. (No model.)

To all whom it may concern:

Be it known that we, ALBERT W. MENNS, a resident of Revere, in the county of Suffolk, and ALBERTO T. VAN HORN, a resident of 5 Malden, in the county of Middlesex, State of Massachusetts, citizens of the United States of America, have invented certain new and useful Improvements in Supports for Engines, of which the following is a specification.

10 Our invention relates to a means for supporting engines upon vehicles, being particularly adapted for use with various classes of cycles having a single steering-wheel. It has for its objects the features hereinafter described and claimed.

15 In the drawings, Figure 1 shows a partial side elevation of the front portion of a bicycle having an engine mounted thereon by one form of our improved support. Fig. 2 is a 20 top plan view thereof. Fig. 3 is a side elevation with the engine, wheel, and connections removed, showing more particularly the supporting members. Fig. 4 is a front elevation thereof. Fig. 5 is a top plan view. Fig. 25 6 is a bottom plan view. Fig. 7 is a top plan view of one of the securing-brackets. Fig. 8 is a similar view of the fork-crown, showing a second pair of brackets formed therewith; and Fig. 9 is a top plan view of the support-30 ing-plate upon which the engine rests.

Similar characters indicate like parts throughout the several figures of the drawings.

A vehicle, in this instance a bicycle, only a 35 portion of which is shown, is designated by the letter B, comprising the head b, handle-bar b', fork-crown b², and front forks b³, with adjoining parts and a portion of the front wheel b⁴. Upon this bicycle is mounted an 40 engine E, which may be conveniently of the explosive type, it being geared to the wheel by some suitable means—as, for example, a chain C, operating over suitable sprockets.

We have found that an effective point to 45 mount an engine upon a bicycle is in proximity to the front or steering wheel, it being geared thereto, and this renders it desirable that the engine shall swing with said wheel in its steering movement, so that the relation

between the elements of the gearing may remain constant. It should also be located below the center of gravity of the vehicle and as nearly as possible symmetrical with regard to the central vertical plane to increase the stability of the system and in such relation to the steering-wheel that steadiness and ease in guiding shall be secured. For this purpose the engine is shown as mounted below the head at the rear of the steering-wheel to move laterally therewith, the cycle preferably 50 having its forks b³ of special shape adapted to receive the engine between them. As illustrated, the fork-crown is of considerable width to secure the proper space between the forks. This crown receives near each end a 55 substantially vertical member of the forks, here shown as double, and consisting of pieces of tubing 10 lying in a plane at the rear of the wheel. To the lower end of each pair of vertical members may be secured an intermediate member 11, conveniently a casting, formed with an arm 12 extending in toward the wheel. To this arm is secured a substantially horizontal member 13, preferably formed of oval tubing, lying parallel to the 60 plane of the wheel and extending in opposite directions from the intermediate member. Its forward arm reaches to the desired distance in front of the head and terminates at its outer end in a fork end 14, which receives 65 the axle of the front wheel, and the rear or inner portion or arm extends into proximity with the vertical portion of the forks, where it is fixed to projections 14' from a supporting-plate 15. Upon this plate some part of 70 the engine, here shown as the crank-casing, may rest and be bolted thereto. To steady and further support the engine, it may be secured at or near the top by a brace or arm 75 16, conveniently bolted to the under side of 80 the fork-crown and having a projection 16' extending into a recess in the cylinder and secured therein by a screw 16", threaded through the projection into the cylinder.

To strengthen the forks and furnish additional support for the engine, one or more members 17 may be provided extending from the outer portion of the forks to the head. 95

As here illustrated, this consists of a piece of tubing secured at one end to a fork end, from which it passes up through and is fixed in a bracket 18, preferably formed as an integral extension from the fork-crown, then extends substantially parallel to the head, and is clamped in one arm of a double bracket 19, extending from and movably secured to the handle-bar stem. It then crosses the head to the opposite side and descends, this branch being fixed in the same manner to the other arm of the bracket 19 and to a second bracket 18 and terminates at and is secured to the fork end at that side of the wheel. In addition to acting as a stay the member 17 may have delivering to it a pipe 20 from the engine-exhaust and serves as a muffler therefore, the discharge into the atmosphere being through small openings 21, preferably situated near the lower end of the tubing at each side of the wheel. The stay may also conveniently support other portions of the equipment, the fuel or hydrocarbon tank 22 being shown as mounted upon them in a position parallel to the head.

It will be seen that as the engine is situated at the lower portion of the cycle below the center of gravity its weight will have no tendency to make the machine top-heavy, while the heat and odor therefrom will be removed to the greatest possible distance from the rider. The weight of the engine upon the rear of the steering-wheel will exert a constant tendency to hold said wheel in a central position, and thus greatly increase the steadiness of steering, while the increased length of wheel-base aids in giving stability to the cycle. The engine is effectively protected by the forks from injury by falls and collisions, and the whole supporting structure is strong and simple. While on account of the marked advantages arising from the effect of the engine in aiding to hold the wheel to a straight course our support is perhaps of greatest utility in connection with a vehicle having a single steering-wheel, it will be obvious that it might be otherwise used and still fall within the spirit of our invention.

Having thus described our invention, we claim—

1. The combination with a cycle, of engine mechanism supported wholly at the rear of the steering-wheel to swing therewith in its steering movement whereby the weight of said engine mechanism will exert a constant tendency to maintain the steering-wheel in a central position.

2. The combination with a cycle, of an engine supported at the rear of the steering-wheel beneath the fork-crown and connected therewith.

3. The combination with a cycle, of an engine supported between the forks of a single steering-wheel and at the rear of said wheel.

4. The combination with a cycle, of an engine supported between the forks of the steering-wheel to swing therewith in its steering

movement and an arm secured to the engine and fork-crown.

5. The combination with a cycle having the forks of the steering-wheel so formed that a portion thereof will lie in a plane at the rear of the wheel, of an engine supported between the forks.

6. The combination with a cycle having the forks of the steering-wheel so formed that a portion thereof will lie in a plane at the rear of the wheel, of an engine supported between the forks, and arms connecting the engine and forks.

7. The combination with a cycle having forks extending downward in a substantially vertical direction from the crown and then forward in a substantially horizontal direction, of an engine mounted between the forks.

8. The combination with a cycle having forks comprising a substantially vertical member and a substantially horizontal member extending therefrom in opposite directions, of an engine supported at one end of the horizontal members.

9. The combination with a cycle having forks comprising a substantially vertical member and a substantially horizontal member extending therefrom in opposite directions, one of the ends of the horizontal members lying in proximity to the vertical members, of an engine supported by the horizontal members between the vertical members.

10. The combination with a cycle, of an engine supported between the forks of one of the wheels, and a stay extending from at or near the outer portion of the forks to a point upon the cycle above the forks.

11. The combination with a cycle, of an engine supported upon the forks of the steering-wheel to swing therewith in its steering movement, and a stay extending from at or near the outer portion of the forks to a point upon the cycle above the forks.

12. The combination with a cycle, of an engine supported upon the forks of the steering-wheel to swing therewith in its steering movement, and a stay connected with the outer portion of the forks and with an extension from the fork-crown.

13. The combination with a cycle, of an engine supported upon the forks of the steering-wheel to swing therewith in its steering movement, and a stay connected with the outer portion of the forks and with an extension from the handle-bar stem.

14. The combination with a cycle, of an engine supported upon the forks of the steering-wheel to swing therewith in its steering movement, and a stay connected with the outer portion of the forks and with an extension from the fork-crown and an extension from the handle-bar stem.

15. The combination with a cycle, of an engine supported upon the forks of the steering-wheel to swing therewith in its steering movement, a stay extending from at or near the outer portion of the forks to a point upon

the cycle above the forks, and a fuel-tank mounted upon said stay.

16. The combination with a cycle, of an engine supported upon the forks of the steering-wheel to swing therewith in its steering movement, a hollow stay extending from the forks to a point above the forks, and means for delivering the engine-exhaust to the stay.

Signed by us at Boston, Massachusetts, this
18th day of January, 1902.

ALBERT W. MENNS.
